UNITED STATES PATENT OFFICE.

LARKIN RICHARD SHAFFER, OF GARLAND, UTAH.

SWITCH-STAND LOCK.

Application filed June 2, 1924. Serial No. 717,360.

To all whom it may concern:

Be it known that I, LARKIN RICHARD SHAFFER, a citizen of the United States, residing at Garland, in the county of Box Elder and State of Utah, have invented certain new and useful Improvements in Switch-Stand Locks; and I do hereby declare the following to be a full, clear, and exact description of the same, reference being had to the accompanying drawings, forming part of this specification.

This invention relates to switch stand locks and has for one of its objects the provision of a locking mechanism for the switch operating lever that will be inexpensive, of simple construction, and easily installed in switch stands of the usual types now in use.

A further object of the invention is to provide a locking mechanism that will not only effectively lock the switch lever but one that will be maintained in or returned to its locking position by gravity.

With these and other objects in view the invention consists in certain novel details of construction, and arrangements and combinations of parts all of which will be herein-after more fully described and the novel features thereof particularly pointed out in the appended claims.

30 In the accompanying drawings,—

Figure 1 is a side elevation of the upper portion of a switch stand containing the present improvements.

Fig. 2 is an end elevation of the same.

35 Fig. 3 is a vertical sectional view taken on the line 3—3 of Fig. 2.

Fig. 4 is a general view of the entire switch stand.

40 Figs. 5 and 6 are detail views of the lever obstructing member.

Fig. 7 is a detail view of the pivoted end portion of the switch lever.

45 Figs. 8 and 9 are detail views of the operating arm for manipulating the obstructing member.

The switch stand shown in Fig. 4 is of the type now in general use, comprising a vertical tubular member 10 in which the shaft of target 11 is journaled and a similar 50 tubular member 12 in which is enclosed a portion of the switch operating connections, and as is common in the art, the table 13 of the switch stand has a recess or notch 14 in its periphery in which the switch operating lever 15 engages when said lever is in its normal depending vertical position.

As is understood, the switch operating lever 15, which is pivoted on a pin 16 in the casing 17, normally occupies a depending position in engagement in recess 14 as 60 before stated, and it is locked in this position by a suitable lock engaging in an eye 18 in a projection or lug 19 on the lever whereby said lever cannot be removed from notch 14 and elevated due to the reduced 65 width of the opening 20 in the casing through which the projection 19 must pass when the lever is returned on its pivot. This lock prevents unauthorized persons operating the switch and forms no part of the 70 present invention as its construction is such as is ordinarily found in this art.

The lock of the present invention, however, comprises an obstructing member, in the form of a ring 21, that is adapted to be 75 interposed between the upper pivoted end of lever 15 and a rigid abutment 22 such as a cross pin mounted in casing 17. Preferably the upper end of said lever is recessed or cut away as at 23 to insure the ring 80 member 21 seating firmly against the lever when positioned between the lever and said abutment. When the ring is in this position the lever 15 cannot possibly be turned on its pivot to move out of notch 14 and assume a horizontal position, such as is necessary before the lever can be revolved in a horizontal plane to throw the switch, but to permit such a movement of the lever at times when an authorized person desires to 85 operate the switch means are provided for temporarily removing the obstructing ring from between the ring and the lever.

Such means for removing the obstructing member preferably take the form of a 95 crank 24, journaled in the casing 17, on which said ring member 21 is loosely carried, and at each of its ends said crank is provided with an operating arm 25 located on the exterior of the casing whereby 100 the crank can be rotated on its axis to remove the ring from its obstructing position.

To insure the ring member invariably returning to its locking or obstructing position the crank 24 and its operating arms 25 project from the axis of the crank in different radial planes, the crank being offset, so to speak, with respect to said arms towards the lever 15.

110 Due to this construction, when the operating arms are rotated to raise the ring

member up from between lever 15 and abutment 22 to the position shown in dotted lines in Fig. 3, the crank proper will be brought to rest by jamming against the abutment 5 before said arms either assume or pass a vertical position or their upper dead center. As the arms 25 normally occupy a depending vertical position the crank thus limits the movement of said arms to an arc 10 of less than 180° and as the arms cannot, therefore, assume or pass a vertical upward position their weight, as well as the weight of the crank itself, will insure the ring dropping back or returning by gravity, to 15 its obstructing position immediately upon the switch lever 15 being returned to its normal depending position. This, in effect, means that there is little, if any, possibility of the locking ring remaining unintentionally in its upper or unobstructing position because, in the absence of any support for the lever 15, said lever must necessarily drop back to its normal position and said ring will consequently be free to be returned 20 by gravity to its obstructing position as just described.

What I claim is:

1. In a switch stand lock, the combination of a casing, an abutment within the 30 casing, a lever adapted to normally occupy a depending position, a crank journaled in the casing, a ring member carried by the crank and interposed between the abutment and lever when the latter is in normal position, and an arm on the crank on the exterior of the casing for rotating said crank about its axis to remove the ring from 35 between the abutment and lever.

2. In a switch stand lock, the combination of a casing, an abutment within the 40 casing, a lever adapted to normally occupy a depending position, a crank journaled in the casing, a ring member carried by the crank and interposed between the abutment and lever when the latter is in normal position, and an arm on the crank on the exterior of the casing for rotating said crank about its axis to remove the ring from 45 between the abutment and lever, said crank 50 and arm projecting from a common pivotal center in different radial planes and having their movement limited to an arc of less than 180°.

3. In a switch stand lock, the combination of a casing, an abutment within the 55 casing, a lever adapted to normally occupy

a depending position, said lever having a recessed end portion, a crank journaled in the casing, an obstructing member carried by the crank and interposed between the 60 abutment and the recessed end portion of the lever when the latter is in normal position, and an arm on the crank on the exterior of the casing for rotating said crank about its axis to remove the obstructing 65 member from between the abutment and lever.

4. In a switch stand lock, the combination of a casing, an abutment within the 70 casing, a lever, a crank journaled in opposite sides of the casing and having an arm on the exterior of the casing, said crank and arm extending from their axis in different radial planes and the movement of said crank being limited by the abutment 75 to limit the movement of the crank and arm and prevent the latter assuming or passing a vertical position, and a ring member carried on said crank and normally positioned between said abutment and lever. 80

5. In a switch stand lock, the combination of a casing, a normally depending lever pivoted in the casing, an abutment within the 85 casing, and a crank journaled in the casing intermediate said abutment and the pivotal center of the lever, and an obstructing member on the crank interposed between the abutment and lever, said crank having an operating arm on the exterior of the casing for revolving said arm and removing said obstruction; said crank, obstructing member, and operating arm being automatically returnable and held in their obstructing positions by gravity whenever the lever assumes its normal position. 95

6. In a switch stand lock, the combination of a casing, a normally depending lever pivoted in the casing, an abutment within the 100 casing, a crank journaled in the casing, and an obstructing member on the crank interposed between the abutment and lever, said crank having an operating arm on the exterior of the casing from revolving said crank and removing said obstruction, said crank with respect to its operating arm being offset toward the pivotal center of the 105 lever whereby said crank, obstructing member and operating arm will be automatically returned and held in their obstructing positions by gravity when the lever assumes 110 its normal position.

LARKIN RICHARD SHAFFER.
